UNITED STATES PATENT OFFICE.

FRANK I. ELLIS, OF PITTSBURGH, PENNSYLVANIA.

CHARGING MACHINE FOR PIPE MILLS.

Application filed March 5, 1924. Serial No. 697,028.

To all whom it may concern:

Be it known that I, FRANK I. ELLIS, residing at Pittsburgh, in the county of Allegheny and State of Pennsylvania, a citizen 5 of the United States, have invented or discovered certain new and useful Improvements in Charging Machines for Pipe Mills, of which improvements the following is a specification.

10 My invention relates to improvements in charging machines for heating furnaces used in conjunction with pipe mills. The object in view is to cause the article which is being conveyed to be more perfectly responsive to the driving impulse which the table imparts to it.

A charging machine adapted for use in connection with a pipe-mill furnace is illustrated in the accompanying drawings. 20 Fig. I is a view of the machine in plan from above. Fig. II is a view of it in side elevation. Figs. III and IV are views in detail drawn to a larger scale; both of these are views in vertical section; the plane 25 of section in Fig. III is longitudinal with respect to the machine, and the plane of section in Fig. IV is transverse with respect to the machine. In Fig. IV the plane of section for Fig. III is indicated by the 30 dotted line III—III, and similarly in Fig. III, the plane of section for Fig. IV is indicated by the dotted line IV—IV. Fig. V is a view in plan from above of the assembly of Figs. III and IV. Figs. VI and 35 VII show in plan from above, and in transverse vertical section, a modification of the nozzle which forms part of the structure of Figs. III and V. Figs. VIII and IX show in longitudinal and transverse sections a 40 roller for the machine modified in its structure, and in itself containing the feature in which my invention resides.

Referring first to Figs. I and II, the table of the charging machine is there 45 shown to be composed of a succession of rollers 1, 2, 3, and 4, set in parallelism, and in this case arranged in pairs, the rollers of each pair arranged at relatively short 50 intervals one from another. These rollers are all of them positively driven upon stationary axes by such means as are indicated in Fig. I, or equivalent means, and all of the rollers are driven uniformly in direction 55 and speed. The rollers of such a conveyor, so driven, are commonly spoken of as "live" rollers. The source of power in this in-

stance is shown to be a motor 5. Understanding the rollers to be rotating in anti-clock-wise direction as seen in Fig. II, it will be understood that the table is then 60 active to carry in right to left direction, articles laid upon it. A skidway formed of a succession of angle bars 6, 7, 8, 9, 10, and 11 is shown, adapted to receive and carry material in preparation for placement upon 65 the table itself. In Figs. II and III a pile of skelp S is shown to be resting upon this skidway. In the operation of the mill it will be understood that such a pile of skelp is assembled on the skidway adjacent to the 70 table and that attendant workmen remove the skelp one by one (or two by two, if preferred), from the pile, and place them upon the table, by which they are automatically carried to the furnace. 75

The problem is to cause the skelp to be freely responsive to the impulsion of the table. Skelp is relatively long and relatively flexible material, and it is desirable that it shall receive immediately and from 80 end to end, or approximately so, the impulsion of the table, to the end that it shall advance smoothly and acquire momentum to carry it to the desired place, as for example, 85 to the hearth of a heating furnace.

In my invention is found a succession of nozzles 12 arranged between the rollers of each pair, and I connect these nozzles through an evacuation pipe 13, and I cause air to be exhausted through the pipe 13, 90 to the end that suction shall be exerted upon the article which shall overlie the nozzle.

Referring particularly to Figs. III and IV, it will be seen that the nozzles 12 have an intake which extends in substantially 95 horizontal plane, and the plane is substantially coincident with the plane tangent to the upper surfaces of both of the adjacent rollers. The intake furthermore is formed as a grid; and, with attention directed upon Figs. III and IV, it will be understood that when skelp A taken from the pile S is laid upon the rollers 1 and 2, it will overlie the nozzle 12, and that because of the suction exerted through this nozzle, 100 the skelp A will be the more closely held in tangency upon the roller surfaces, and be more immediately and entirely responsive to the drive which the rollers impart to it, impelling it in right to left direction (Figs. 110 II, III).

Comparing Figs. VI and VII with Figs.

V and IV, it will be perceived that the nozzles may be modified in shape and provided with a stop or abutment at 14. Speaking with more precision, the grid with which 5 the nozzle is equipped may be removable, and in place of the grid shown in Figs. IV and V, such a grid as that shown in Figs. VI and VII may be introduced. The grid in the latter case has two features; one is 10 that the effective area of the nozzle is reduced, increasing the suction effect, the other is that the stop 14 is provided against which the applied skelp may be aligned, and in consequence, caused to advance in an 15 accurately defined course.

In the modification illustrated in Figs. VIII and IX, the suction nozzle is merged in the formation of the roller itself. Here the roller takes the form of a hollow drum 20 15, and the cylindrical face of this hollow drum is of grid form. Concentrically mounted within the drum is a non-rotatable nozzle 16, with a suction connection 17. The hollow drum is rotated and serves to impel 25 the skelp, and always as it rotates there is a suction effect at the highest point, where skelp rests upon it, and so the same general end is achieved as in the form shown in the earlier figures.

30 In speaking of the structures of Figs. III and IV, I said that the intake of the nozzle extended in a plane substantially coincident with the plane tangent to the adjacent rollers 1 and 2. It is, in point of fact, disposed slightly lower than that tangent plane, for thus the skelp may be held more effectively to contact with the rollers.

I should have said before, in speaking of 40 the table as shown in Figs. I and II, that it is a movable table, mounted upon tracks 18, and that it carries motor 19, by which it may be shifted along the tracks from place to place. At one point it may receive from the cooling beds of a rolling-mill its load

of skelp in the form of the pile S, and at 45 another point it may deliver its load, piece by piece, in the manner described, to the heating furnace of a welding machine.

I claim as my invention:

1. In a charging machine for a pipe mill 50 in combination with a plurality of rollers positively rotated upon stationary axes and adapted to drive forward skelp resting upon them, suction means acting from beneath upon the applied material, and holding it to 55 firmer contact with the rollers.

2. In a charging machine for a pipe mill a conveyor table formed of "live" rollers, each positively rotated upon a stationary axis, and suction means including a nozzle 60 arranged beneath the pathway of advance of material upon the conveyor table.

3. In a charging machine for a pipe mill a conveyor table consisting of a plurality 65 of rollers positively rotated upon stationary axes and arranged in parallel succession, means for feeding a skelp to such conveyor table in a direction parallel to the axes of the roller, and a succession of suction devices, each including a nozzle arranged beneath the pathway of advance of the material upon the conveyor table and at successive points in the length of the conveyor 70 table.

4. In a charging machine for a pipe mill, 75 a conveyor table formed of live rollers, each turning upon a stationary axis, said rollers adapted to receive and to sustain and to impel skelp resting by gravity upon them, one 80 of said rollers being hollow and provided with an orificed surface, in combination with means for exerting suction through the orificed surface of the roller last named upon skelp resting by gravity upon it.

In testimony whereof I have hereunto set 85 my hand.

FRANK I. ELLIS.
